DESIGN FOR A DESK

Raymond L. Myers, United States Army,
Broome County, N. Y.

Application February 7, 1945, Serial No. 117,796

Term of patent 14 years

(Cl. D33—7)

To all whom it may concern:

Be it known that I, Raymond L. Myers, United States Army, a citizen of the United States, residing at Broome County, State of New York, have invented a new, original, and ornamental Design for a Desk, of which the following is a specification, reference being had to the accompanying drawing, forming a part thereof.

The single figure in the drawing is a rear perspective view of the desk, showing my new design. The front and left sides of the desk which are not shown in the drawing are plain, flat surfaces.

I claim:

The ornamental design for a desk, as shown and described.

RAYMOND L. MYERS.
